PERMANENT LOOSE LEAF BINDER

Filed July 7, 1927

BY

INVENTOR.

INVENTOR.
Lewis Barnes

ATTORNEY

UNITED STATES PATENT OFFICE.

LEWIS BARNES, OF FARMINGTON, MICHIGAN.

PERMANENT LOOSE-LEAF BINDER.

Application filed July 7, 1927. Serial No. 203,951.

My invention relates to a new and useful improvement in a permanent loose leaf binder adapted for use in binding loose leaves permanently on a supporting member.

5 The device is particularly useful in binding checks on a check holder so that, while the checks are being written, the same may lie flat and the stubs thereof be permanently bound on the holder.

10 It is an object of the invention to provide a binder of this class which will be simple in structure, economical of manufacture and highly efficient in use.

Another object of the invention is the provision in a binder of this class of a holding member on which the securing member may be easily and quickly fastened after projection of the same through the loose leaves.

15 Other objects will appear hereinafter.

20 The invention consists in the combination and arrangement of parts hereinafter described and claimed.

The invention will be best understood by a reference to the accompanying drawings 25 which form a part of this specification and in which,

Fig. 1 is a perspective view of the invention in exploded form.

Fig. 2 is a perspective view of the invention mounted on a suitable support.

Fig. 3 is a longitudinal sectional view of the invention shown mounted on a suitable support.

Fig. 4 is a sectional view taken on line 35 4-4 of Fig. 3.

Fig. 5 is a perspective view of a modified form of the invention.

Fig. 6 is a longitudinal central sectional view of Fig. 5.

40 In the drawings I have illustrated the invention used with a supporting member 7 which may be made from card board or other suitable material. The supporting member 7 is reinforced by a fabric layer 8 and is provided with holes 9. The bottom of the holder 7 is also reinforced with fabric reinforcement 10.

The invention comprises a securing member embodying the plate 11 preferably made 50 from metal and projecting from the sides of which are the prongs 12 which may be of any desired number. These prongs are adapted for insertion through the openings 9. The prongs will fold upon the supporting member 7, as clearly appears from Fig. 3, to secure the holding member in position

on the support 7. This holding member is provided with the longitudinally extending groove 13 which is enlarged, surrounding the openings 14 and 15 which are formed in the 60 plate 11. The groove 13 is adapted for the reception of a pin 15' which is positioned in the groove prior to the fastening of the plate 12 on the support 7. A securing member comprising the U shaped staple 16 is bifurcated at its ends to provide the spaced prongs 17 and 18, the space between the prongs 17 and 18 being preferably less than 65 the diameter of the pin 15'.

In use, after the plate 11 is mounted on 70 the supporting member 7, with the pin 15' in position, the loose leaves are positioned upon the securing member 16 upon which the ends of the legs of this securing member are thrust into the openings 14 and 15 so that 75 the prongs 17 and 18 will straddle the pin 15'. By enlarging the raised portion of the plate 11 around the openings 14 and 15 the ends of the legs clear the raised portion of the plate 11 prior to straddling the 80 pin 15'. By thrusting the securing member 16 into the openings 14 and 15, the prongs 17 and 18 will be spread apart by the pin 15', these prongs being permanently distorted out of their normal position and 85 being spaced apart permanently a distance greater than the diameter of the openings 14 and 15, so that a withdrawal of the securing member 16 from attachment with the plate 11 is prevented. In this manner the 90 staple is clinched to the plate 11 and the loose leaves positioned upon the securing member 16 permanently fastened in position to the supporting member 7.

With a binder of this class any number 95 of binding members may be mounted on the supporting member 7 as these plates 11 may be placed at desired points.

It is thus seen that I have provided a holding member which is mounted on a suitable 100 support and on which the securing member comprising the U shaped staple 16 is permanently fastened by a distortion of the engaging ends of the securing member 16.

In the modified forms shown in Figs. 5 105 and 6 I have provided the U shaped securing member 16 which is secured on the pin 15' in the manner already described. Instead of the plate 11 I have provided an arrangement whereby plate 11 and the supporting member 7 are formed in one. To this end I have utilized a supporting member 7' made pref-

erably of metal having one end 19 doubled upon itself and this doubled-over portion again doubled upon itself to provide a resilient clamping device adapted for clamping the check book cover 20 with which the device is used, a spacing block 21 is positioned between the main body 7' and the doubled-over portion to facilitate entry of the member 20 therebetween.

10 In use these retainers are generally inserted into a retaining pocket formed in a check book cover. With the forms shown in Figs. 1 to 4 the supporting member 7 would be insertable into the pockets. In 15 the form shown in Figs. 5 and 6 the member 7' would be inserted into the pockets of the cover, the outer side 20 of the pocket being clamped between the main body 7 and the doubled-over portion. With the form 20 shown in Figs. 1 to 4 it would be necessary to have the checks perforated at predetermined positions while with the forms shown in Figs. 5 and 6 this becomes unnecessary as these retainers may be located at any 25 desired point transversely of the cover.

While I have illustrated and described the preferred form of my invention I do not wish to limit myself to the precise details of structure shown, but desire to avail 30 myself of such variations and modifications as come within the scope of the appended 35 claims.

Having thus described my invention what I claim as new and desire to secure by Letters Patent is:

1. A loose leaf binder of the class described comprising: a holding member having openings formed therein; a securing member having spaced legs, each provided 40 with spaced prongs at the ends, the ends of said legs being insertable through said holes; and means engageable with said prongs for spreading said prongs after insertion through said openings.

45 2. A permanent binder of the class described comprising: a holding member having openings formed therethrough; a diametrically projecting spreading member extending across said openings; a securing member having its ends doubled upon each 50 other and bifurcated, the prongs in said ends being adapted for projecting into said openings and straddling said spreading member, said prongs, upon spreading, permanently 55 attaching said securing member on said holding member.

3. A binder of the class described comprising: a holding member having openings

formed therein; a spreading member projected across said openings; a securing member having its ends doubled upon each other and provided with prongs, said prongs being spaced apart a distance less than the thickness of said spreading member, said ends being projectable through said openings, said prongs straddling said spreading member, said spreading member effecting the spreading apart of said prongs for clinching said securing member on said holding member.

4. A binder of the class described comprising: a holding member having a longitudinally extended raised portion and provided with openings formed in said raised portion, said raised portion being widened 60 at said openings; a spreading member engaging in said raised portion and projecting across said openings; a substantially U shaped securing member having its ends bifurcated adapted for projecting through 65 said opening, the prongs straddling said spreading member, said spreading member being of greater thickness than the space separating said prongs and effecting a spreading of said prongs for clinching said 70 securing member on said holding member.

5. A binder of the class described comprising: a holding member having a longitudinally extended raised portion and provided with openings formed in said raised portion, said raised portion being widened 75 at said openings; a spreading member engaging in said raised portion and projecting across said openings; a substantially U shaped securing member having its ends bifurcated adapted for projecting through 80 said opening, the prongs straddling said spreading member, said spreading member being of greater thickness than the space separating said prongs and effecting a spreading of said prongs for clinching said 85 securing member on said holding member.

6. A binder of the class described comprising: a supporting member having one end doubled upon itself and doubled over and doubled upon the main body and in spaced relation thereto; and a retaining member permanently fastened on and projecting upwardly from the outer face of 90 said doubled-over portion.

In testimony whereof I have signed the foregoing specification.

LEWIS BARNES.
